UNITED STATES PATENT OFFICE.

DAVID E. BOWN, OF PITTSBURG, PENNSYLVANIA.

SOCKET FOR INCANDESCENT ELECTRIC LAMPS.

No. 921,199.

Specification of Letters Patent.

Patented May 11, 1909.

Application filed March 6, 1906. Serial No. 304,430.

To all whom it may concern:

Be it known that I, DAVID E. BOWN, a resident of Pittsburg, in the county of Allegheny and State of Pennsylvania, have invented a new and useful Improvement in Sockets for Incandescent Electric Lamps; and I do hereby declare the following to be a full, clear, and exact description thereof.

My invention relates to sockets for incandescent electric lamps, and has for its object to provide a cheap, simple and efficient form of a socket, which will be easy to construct and install, will do away with the objectionable screws so commonly employed, and will also fully protect and insulate the various metallic parts.

My invention consists, generally stated, in the novel arrangement, construction and combination of parts as hereinafter more fully set forth and described and particularly pointed out in the claims.

To enable others skilled in the art to which my invention appertains to construct and use my improved socket, I will describe the same more fully, referring to the accompanying drawing, in which—

Figure 1 is a vertical central section of my improved socket for incandescent electric lamps in double pole form. Fig. 2 is a side elevation of the base or block employed looking at the rear face of the same and showing some of the parts in section. Fig. 3 is a like view of said block looking at the front face of the same. Fig. 4 is a cross-section of the block on the line 4—4 Fig. 2 and looking in the direction of the arrow. Fig. 5 is a like view on the line 5—5 Fig. 1 and looking in the direction of the arrow. Fig. 6 is a perspective view of the cam employed. Figs. 7 and 8 are side elevations of the base or block, partly in section, and showing the same for use with a single pole socket. Fig. 9 is a sectional view showing my invention applied for use with a keyless socket and showing another manner of attaching the shell to the block.

Like symbols of reference herein indicate like parts in each of the figures of the drawing.

As illustrated in said drawing 1 represents a single or solid head base or block of porcelain or other suitable insulating material which is provided with the upper and lower annular flanges 2, 2' thereon and between which is the partition or center wall 3. This

wall 3 forms the recesses 3' on each side thereof and has the connecting and extending portion 4 projecting out on one side of the same. The lower flange 2' on the block 1 is connected to the threaded metallic shell 5 forming the outer terminal of the lamp by an annular grooved seat 5' formed in the inner end of said shell by the metal of the said shell being bent over the said flange, as at 5''. This shell 5 fits within an outer shell or casing 6 which has a lining 7 of insulating material within the same, while to the upper end of said casing 6 is attached the metallic cap 8 having the usual threaded attachment nipple 9 formed on the curved end 10' thereof. The cap 8 has an annular seat 10 formed therein for the upper flange 2 of the block 1 by means of the curved end 10' and annular rib 10'' on said cap, and such cap is connected to the outer casing 6 by means of the threaded portion 9' adjacent to said rib engaging with a like threaded portion 6' on the inner end of said casing. The openings 6'' and 8'' are formed in said casing 6, lining 7 and cap 8 respectively, which when the parts are in position will form the hole 8' through the same and within said hole is the spindle 11' of the key or thumb-piece 11. This spindle 11' has a threaded seat 11'' therein for being engaged by the threaded end 12' on the cam-bar 12 and when in position the inner end of said spindle abuts the shoulder 12'' formed on said cam-bar and adjacent to said end 12'.

The cam-bar 12 fits within an opening 3'' formed in the center wall 3 and extension 4 of the block 1 and its opposite end is provided with a cam 13 formed of porcelain or other insulating material, which is secured thereto by means of a nut 14 engaging with such threaded opposite end 14' and fitting within a seat 14'' formed in the face of said cam.

Extending through the center wall 3 of the block 1, are the terminals 15, 15' to which the wires 16, 16' are connected on one side of said wall, such terminals being located on each side of the extending portion 4 in said center wall, so that the wires in passing through the nipple 9 of the cap 8 and through holes 16'' in the upper flange 2 of said block to said terminals will be separated by said portion 4. A spring contact point 17 extends up in front of one of the terminals 15 and on the opposite side of the wall 3 from the wires 16 and 16'.

this contact point is connected to the bent edge 5" on the shell 5 fitting over the lower block flange 2', while another spring contact point 17' extends up in front of the other terminal 15' and on the same side of the wall 3 as the contact point 17. This contact point 17' is connected to a central lamp terminal 18 located on the outer face of the flange 2' on the block 1 by means of a screw 19 connecting these parts through said flange 2' and such lamp terminal 18 is provided with a spring contact lip or piece 18' thereon. The ends 13' of the cam 13 are adapted to fit between the free ends of the spring contact points 17, 17' and the terminals 15, 15' to make and break the circuits, and the opposite sides of each of said ends are beveled down, as at 13" in order to facilitate such ends to be placed between such contact points for working.

In Figs. 7 and 8 my improved socket for incandescent electric lamps is shown in a single pole form in which case only the terminal 15 is used to be engaged by the cam 13 and the spring contact point 17' is done away with. In this form the terminal 15' has a contact plate 19 connected to the same within the wall 3 of the block 1 so that it can extend through an opening 19' formed in said block 30 and be bent or projected into a spring contact 20 along and within a recess 20' formed in the face of the flange 2' on said block to form the central lamp terminal.

In Fig. 9 my invention is shown as applied to a keyless socket and in such case the terminals 15, 15' in the center wall 3 are connected with the shell or outer terminal of the lamp and to the central lamp terminal by the contact points 17, 17' respectively in substantially the same manner as shown in the single pole socket construction. In such figure is also shown another form of attaching the shell 5 to the block, which consists in forming a grooved seat 1' in the lower flange 2' of the block 1 and then bending the inner edge of the shell 5 around the lower edge 2^a of said flange and into said seat 1' and thereby form the grooved seat 5' in said shell for said edge, while the upper edge 2^b of said flange can be extended slightly beyond the lower edge in order to bear against the insulated lining 7 in the casing 6. In the use of this form of shell attachment the contact point 17 for the terminal 15 can be connected to the bent edge 5" of the shell 5 by a screw 17" passing through the lower end of said contact point 17 and through a hole or opening 1" in the upper edge 2^b of the block flange 2' so that it can be screwed into such bent edge of the shell.

It will be obvious that in assembling the parts of my improved socket for incandescent electric lamps that the wires 16 and 16' are drawn through the nipple 9 of the cap 8 and are secured to the terminals 15 and 15'

respectively, on the wall 3 of the block 1 and on each side of the extending portion 4 on said wall, by passing through the holes 16" in the flange 2 on said block. The block 1 is permanently fixed or secured to the cap 8 through the medium of the grooved seat 10' formed in said cap fitting around the flange 2 on said block and is attached to the shell 5 by bending over the ends of the shell to form the groove 5' for the flange 2', so that with the cam-bar 12 and cam 13 in place within the said block the parts are ready for forming the complete socket by placing the shell 5 within the outer casing 6, as shown in Fig. 1. After this is accomplished the cap 8 is screwed up on the casing 6 through the medium of the threaded portion 9' on said cap engaging with threaded portion 6' on said casing which will cause these parts and the block 1 and shell 5 to be secured in place, thereby enabling the shoulder 5^a formed by the grooved seat 5' on said shell to rest against a like shoulder 6^a formed on said casing and also enabling the openings 6" and 8" in said casing and cap respectively to register with each other and form the hole 8'. The spindle 11' on the key or thumb-piece 11 can now be inserted through the hole 8' in the casing 6 and cap and screwed to place against the shoulder 12" on the cam-bar 12 through the medium of the threaded end 12' on said bar engaging with the threaded opening or seat 11" in said spindle thereby forming the complete socket and ready for the lamp (not shown) to be screwed into the shell 5 to contact with the central lamp terminal therein. It will also be obvious that the terminals 15 and 15' are connected and disconnected with the wires 16 and 16' by means of the cam 13 engaging and disengaging by its ends 13' between the spring contact points 17 and 17' and said terminals in the one or double pole form and by one of the ends 13' engaging and disengaging between the spring contact point 17 and the terminal 15 in the other or single pole form. In either case or use as the key or thumb-piece 11 is always turned in one direction, as to the right, the cam 13 will be turned to connect and disconnect with the terminal through the medium of the spindle 11' on said thumb-piece being revolved in the hole 8' and being connected to the bar 12 on said cam, and when said thumb-piece is turned in the opposite direction it will act to unscrew the same from said bar. In case of such reverse turning of the spindle 11 through ignorance or mistake it will soon be apparent, in the failure of the lamp to burn or the removal of the key from the socket and cause the spindle to be turned in the proper direction, although when such spindle is removed from the hole 8' the parts are ready to be disconnected for any cause by the unscrewing of the cap 8 from the

shell or casing 6 and the removal of the said cap, block 1, and shell 5 from said casing.

It will thus be seen that my improved socket for incandescent electric lamps can be easily and quickly assembled by reason of it containing few parts and only requiring the attaching of the cap to the outer shell or casing, while this also permits the convenient and rapid removal of the parts for the purpose of repairing or examination of the same. The socket is also of such a construction that all the vital or important parts are exposed to the eye upon a single block in order to render them easy of access for repairing and other purposes, and all the parts are so arranged as to be protected and away from each other in order to overcome the possibility of any short-circuiting. The socket is so arranged as to overcome all liability of any fires being caused therefrom in any manner, thereby rendering the same fire-proof and being without connecting screws, which are liable to become loose and form a spark rendering the same capable of great utility and safe in use. By reason of being screwless, the socket avoids play of the parts and loss of parts and screws, while the same is easy and economical to manufacture. The socket is also capable of standing exceedingly high voltage, and particularly in the single pole form, by reason of the terminals being insulated by the construction of the block and by reason of the distance between central lamp contact and shell lamp terminal and being screwless. Various modifications and changes in the construction and design of the various parts of my improved socket for incandescent electric lamps other than the ones mentioned herein may be resorted to without departing from the spirit of the invention or sacrificing any of its advantages.

What I claim as my invention and desire to secure by Letters Patent is—

1. In a lamp-socket, the combination of the inner shell, a cap, and a single solid base or block formed of insulating material within said shell and cap having a partition within the same for forming recesses on each side of the same for the terminals and a projecting portion on the side of said partition for separating the connecting wires leading to the terminals.

2. In a lamp-socket, the combination of the cap, a single solid base or block formed of insulating material for the terminals and connecting wires, and connections on said block and between said block and cap for permanently securing said block and cap together to permit said block to be carried by said cap.

3. In a lamp-socket, the combination of the cap having a grooved seat therein, a single solid base or block formed of insulating material for the terminals and connecting wires, and flanges on said block fitting within

said grooved seat for permanently securing said block to said cap to permit said block to be carried by said cap.

4. In a lamp-socket, the combination of the inner shell, a single solid base or block of insulating material for the terminals and connecting wires, a flange on said block, and connections between said shell and flange for attaching said shell to said block.

5. In a lamp-socket, the combination of the inner shell, a single solid base or block of insulating material for the terminals and connecting wires, a flange on said block, and a bent flange on said shell for fitting over the block flange to attach said shell to said block.

6. In a lamp-socket, the combination of the cap, an inner shell, a single solid base or block of insulating material permanently secured within and carried by said cap for the terminals and connecting wires, and an outer casing having a threaded connection thereon for attaching said cap and block thereto.

7. In a lamp-socket, the combination of the cap, a single solid base or block of insulating material permanently secured within and carried by said cap for the terminals and connecting wires, and an outer casing engaging with said cap by a threaded connection.

8. In a lamp-socket, the combination of the cap, a single solid base or block of insulating material permanently secured within and carried by said cap for the terminals and connecting wires, an outer casing, and a cap fitting over and engaging with said casing by a threaded connection.

9. In a lamp-socket, the combination of a base or block of insulating material for the terminals and connecting wires, an outer casing having an opening therein, and a cap having an opening therein and engaging with said casing by a threaded connection and said openings registering with each other when the cap is screwed up, to form a hole for the reception of the key.

10. In a lamp-socket, the combination of the outer casing, a cap, a single or solid base or block of insulating material having a partition or wall within the block for forming recesses on each side of the same for the terminals and connecting wires, and a key passing through said cap and casing and journaled within said wall.

11. In a lamp-socket, the combination of the outer casing, a cap, a single or solid base or block of insulating material having a partition or wall within said block for forming recesses on each side of the same for the terminals and connecting wires and a projecting portion on one side of said wall for separating the connecting wires, and a key passing through said cap and casing and journaled within said wall and projecting portion.

12. In a lamp-socket, the combination of the base or block formed of insulating material for the terminals and connecting wires,

spring contact points, a key, and a removable cam of insulating material on said key for fitting between said terminals and contact points in making and breaking the circuits.

13. In a lamp-socket, the combination of the base or block formed of insulating material for the terminals and connecting wires, spring contact points, a key, and a revoluble cam of insulating material on said key having beveled faces thereon for fitting between said terminals and contact points in making and breaking circuits.

14. As a new article of manufacture, a base or block for incandescent electric lamp-sockets formed of a single solid piece of insulating material having a flange on the lamp end for connecting the same with the inner shell of the socket.

15. As a new article of manufacture, a base or block for incandescent lamp sockets formed of a single solid piece of insulating material having a flange on the cap end for connecting the same with the cap of the socket and a flange on the lamp end for con-

necting the same with the inner shell of the socket.

16. As a new article of manufacture, a base or block for incandescent electric lamp-sockets formed of a single solid piece of insulating material having a partition or wall therein for forming recesses for the terminals and a projecting portion on said wall for separating the wires to the terminals.

17. As a new article of manufacture, a base or block for incandescent lamp sockets formed of a single solid piece of insulating material having a flange at each end of the same and a partition or wall between said flanges provided with a projecting portion on the same for forming recesses for the terminals and for separating the wires to said terminals.

In testimony whereof, I the said DAVID E. BOWN have hereunto set my hand.

DAVID E. BOWN
